INERTIA-POWERED AIR CIRCULATOR

Edmund R. Aller, Gary, Ind., assignor to General American Transportation Corporation, Chicago, Ill., a corporation of New York

Application December 9, 1938, Serial No. 244,838

4 Claims. (Cl. 98—6)

My invention relates to an improved inertia-operated mechanism for circulating air in a railway refrigerator car, or other carrier, which is subject to irregular movements when in motion.

5 My invention is especially adopted for use in freight cars or other carriers for perishable goods in which either refrigeration or heat is provided, and its purpose is to maintain a more uniform temperature throughout the body of the car by 10 promoting or stimulating the circulation of air within the car.

While in motion in a train, a railway car is subject to various parasitic vibrations and pulsations caused by irregularities in the track, wheels 15 out of round, wheels with flat spots, buffing and draft pulsations, and other causes. The car is thus subjected to a reasonably constant oscillation, vertical and in other directions, which persists to an appreciable degree even when snubbing 20 devices are used on the trucks. This oscillation is the source of power utilized in the mechanism herein disclosed.

The primary object of my invention is to provide an improved air-circulating mechanism operated by the inertia of a part of the mechanism with respect to the irregular movements of a railway car above described. By means of my invention a more rapid circulation of air is promoted than now exists by natural convection.

30 Still another object is to provide an air-circulating device which is readily portable and wholly self-contained in one unit of the car so that one or more of the devices may be positioned within the car in manner most effective to stimulate air circulation.

These and other objects are attained by the construction more fully described hereinafter in connection with the accompanying drawing which illustrates the preferred embodiment of 40 my invention.

In the drawing—

Fig. 1 is a longitudinal, vertical section, more or less conventional, of a refrigerator railway car illustrating the several inertia-powered air-circulating mechanisms embodying my invention distributed around the interior of the car;

Fig. 2 is an enlarged top plan view of my inertia-powered air circulator;

Fig. 3 is a longitudinal, vertical, sectional view 50 on the line 3—3 of Fig. 2; and

Fig. 4 is a transverse vertical section on line 4—4 of Fig. 3.

The refrigerator car A shown in Fig. 1, is intended to be representative of the class of cars 55 or carriers for use in which the device of my in-

vention is adapted. The car contains the usual ice bunkers B at the ends, the space in between the bunkers being used for the goods being carried. To illustrate the manner in which these devices may be distributed within the car, one or 5 more of these devices C may be placed beneath each of the ice bunkers with their air outlet or discharge ends directed towards the center of the car to stimulate circulation of the colder air from the locality of the ice bunkers along the floor to- 10 wards the center. Several of these devices may be supported from the ceiling of the car with their outlets directed towards the bunkers so that their effect will be uni-directional and cumulative, thus stimulating the circulation of the 15 warmer air in the upper portion of the car towards the bunkers. Thus the devices stimulate or increase the natural circulation set up by convection, resulting in a more uniform distribution of temperature throughout the interior of the 20 car compartment. If the car is heated, for instance, by charcoal burners placed in the bunkers, then the air circulator devices can be reversed to direct air circulation in the opposite direction to 25 that shown in Fig. 1.

The individual structure shown in the drawing involves generally two rectangular plates or vanes 1 and 2 in hinged relation somewhat after the manner of the leaves of a book in the sense that they are movable relatively to each other 30 from parallel relation to an angular relation, so that as they move towards each other the air is expelled from between them and as they move apart air is drawn in between them ready for the next expelling impulse.

In the present structure the lower plate 1 is the member connected with, or in direct association with, the car structure and thus responsive to the oscillations thereof. The device may be simply placed upon the floor of the car or it may 40 be supported from the ceiling, as shown in Fig. 1, so that it moves as a unit or whole directly with the vibrations or oscillations of the car. The upper plate 2 is the inertia member which tends, because of its inertia, to resist movement imparted to it by the housing. The parts are 45 encased in a casing which is formed by the side walls 3, a top wall 4, and a rear wall D.

In the structure shown, the side walls extend 50 upwardly from the side margins of the lower plate and are preferably arranged so that the clearance between these walls and the margins of the inertia member plate 2 is just sufficient to permit free movement of the member 2 and at the same time to reduce to a minimum the pas- 55

sage of air therebetween. The top wall 4 is formed so that it inclines or is beveled generally downwardly from the rear end to the discharge end of the device, and also from the center portion to the side walls. This construction is provided so as to protect the device from damage by deflecting falling pieces of ice or other objects which may strike the top wall. Likewise this top wall formation effectively drains off water or brine which may drip from ice bunkers above.

The casing forms an air inlet chamber 5 above the inertia vane 2. This chamber is provided with an air inlet 6 at its rear end which, in the present case, is formed by making the rear wall 15 in two sections divided horizontally. The upper section 7 is vertical. The lower section 8 is inclined inwardly at a relatively sharp angle with respect to the floor or plate 1. The upper portion of the casing thus overhangs the lower section 8 of the rear wall so that the air inlet 6 lies in a horizontal plane and air is entered therethrough from below and at the same time water dripping on the device is drained away from the outlet and prevented from entering the interior 20 of the mechanism.

The forward end of the casing is open to provide a discharge outlet 9. The angle of the lower section 8 of the rear wall with respect to the plate 1 forms a suitable bearing or fulcrum 10 for the rear edge or margin of the inertia member 2 into which it is set. Thus a simple pivotal or hinge connection is provided by which the movement of the lower plate is imparted to the inertia member, and which is less likely to be 30 affected by corrosion.

Since the plate member 2 is relatively thin and light in weight and of considerable area, and is more in the nature of a fan or vane effective to displace a considerable volume of air, it does not 40 possess sufficient inertia for the purpose. In order, therefore, to increase the inertia of the member whereby to develop sufficient power, I add considerable weight to the plate 2. This weight is in the form of a transversely disposed 45 block 11 of metal which is attached to the upper side of the plate and is disposed close to the fulcrum of the plate so that the device is rendered sensitive to very small vertical movements because of the multiplying leverage effect relative 50 to the length of the plate. For instance, a half inch relative movement of the weight will result in an inch and a half to two inches of movement of opposite or forward end of the plate 1. An elastic member 12, preferably in the form of a 55 coiled spring or a rubber member, is connected at one end to an eyelet 13 near the forward end of the plate 1 and at its other end to an anchor 15 at the rear end of the casing. This elastic member is preferably arranged to be just sufficient 60 to slightly more than overcome the weight so that it normally tends to hold the plates apart or returns the plate 2 to an upper position after each relative downward stroke of the plate 1. The top wall of the casing serves as a stop for 65 the forward edge of the plate 1. This forward margin 14 of the plate member 1 terminates short of the end of the casing, as shown more clearly in Fig. 3, so that while the plate 1 is separated from the top wall of the casing a passage is 70 formed which provides communication between the upper chamber 5 of the casing and the pump chamber 15 below the member 1.

In operation, as the lower plate member 1 and the casing are carried upwardly by the car in response to the vertical oscillation of the car,

the inertia developed in the weight 11 causes a relative movement of the plates 1 and 2 toward each other, thus causing the air between the plates to be expelled or forced out through the outlet end 9 of the casing. As the plates move 5 apart in response to the spring 12 and the downward movement of the car, air will again be drawn in between the plates, mainly from the upper chamber 5 around the forward margin 14 of the plate member 1, the flow of air entering 10 the intake 6 at the rear end of the device and leaving casing at the forward discharge opening 9 which will be uni-directional, and thus give to the device the advantage of a valve type of pump without the necessity for valves. The series of 15 impulses given to the air, added to the natural convection, stimulates the circulation of air and thus serves to distribute the temperature more uniformly in the interior of the car.

It is obvious that changes may be made in the 20 construction, arrangement, and operation of the various parts, without departing from the spirit of the invention, and I contemplate such changes as fairly fall within the scope of the appended claims.

I claim:

1. In an inertia-powered air circulator of the class described, the combination of a vane subject to the oscillations of the car, an inertia member including a vane pivotally related to said 30 first-mentioned vane and movable toward and from the same for impelling air from between said vanes, a housing for directing the impelled air from one end and having an outlet opening substantially equal in width to the range of movement of said vane, said housing forming an air inlet chamber above said movable vane and having an air inlet opening for said chamber at its end opposite the outlet opening, an elastic member connected to said inertia member and said 40 housing, and acting to overcome the weight of said inertia member sufficiently to move the inertia member vane away from said other vane.

2. In an inertia-operated, portable, self-contained air circulator of the class described, the 45 combination of a housing having a bottom wall with an air outlet opening at one end adjacent said bottom wall, and an air inlet opening at the opposite end, a vane within said housing pivotally related close to said bottom wall at the rear 50 end of said housing and having its forward end adjacent said outlet opening and adapted when moved relatively toward said bottom wall to expel air from between said vane and bottom wall, a weight carried by said vane adjacent to its 55 pivotal end for imparting inertia to said vane, and an elastic means yieldingly acting on said vane to overcome the weight sufficiently to hold the vane separated from said bottom wall.

3. In a self-contained, portable, inertia-operated air circulator of the class described, the combination of a housing having a bottom wall, and side walls, and a top wall overhanging a portion of the bottom wall to form an upwardly directed air inlet at its rear end, and having an 65 air outlet opening at its forward end, said top wall being beveled towards its side and end walls to drain water from said top wall and deflect objects falling upon said top wall, and means within said housing acting to expel air from said outlet opening when the housing is subjected to oscillations of the car in which the device is used.

4. An air-circulating means to be operated by the irregular vertical movements of a railway car when in motion, comprising a housing sup-

ported by said car and having a bottom wall, a movable plate within said housing, one end of said plate being hingedly attached to said housing, a weight fastened upon said movable plate close to said hinge end, a spring attached to said movable plate at the end of said plate opposite the hinged end, said spring being also attached to the housing so as to support flexibly the mov-

able plate spaced from said bottom wall, said housing having an opening at one end for the intake of air on the side of the movable plate to which the spring is attached and the discharge of air from the opposite side of said movable plate. 5
